UNITED STATES PATENT OFFICE.

WILLIAM R. NEWTON, OF INGLESIDE, ILLINOIS.

DESIGN FOR A ROCKING TOY.

44,345.

Specification for Design.

Patented July 15, 1913.

Application filed August 9, 1912. Serial No. 714,314. Term of patent 7 years.

To all whom it may concern:

Be it known that I, WILLIAM R. NEWTON, a citizen of the United States, residing at Ingleside, in the county of Lake and State of Illinois, have invented a new, original, and ornamental Design for Rocking Toys, of which the following is a specification, reference being had to the accompanying drawing, forming part thereof.

The figure is a perspective view of a rocking toy, showing my new design.

I claim:

The ornamental design for a rocking toy, as shown.

WILLIAM R. NEWTON.

Witnesses:

HARRY KAPING,
GUS HUHN.
